ROLL-ON DISPENSER

Ira H. Miller, Lambertville, Mich., assignor to Owens-Illinois Glass Company, Toledo, Ohio, a corporation of Ohio

Filed Mar. 7, 1961, Ser. No. 64,171

Term of patent 14 years

(Cl. D58—26)

The side and end not shown are substantially like the side and end shown.

The portions shown in broken lines are for illustrative purposes only.

I claim:

The ornamental design for a roll-on dispenser substantially as shown and described.
